UNITED STATES PATENT OFFICE.

WILLIAM F. VEBER, OF BOWLING GREEN, OHIO, ASSIGNOR OF ONE-HALF
TO ALLAN W. RUDULPH, OF SAME PLACE.

OVERSEAMING ATTACHMENT FOR SEWING-MACHINES.

SPECIFICATION forming part of Letters Patent No. 292,451, dated January 22, 1884.

Application filed June 22, 1883. (No model.)

To all whom it may concern:

Be it known that I, WILLIAM F. VEBER, of Bowling Green, in the county of Wood and State of Ohio, have invented an Improved Overseaming Attachment for Sewing-Machines, of which the following is a specification, reference being had to the accompanying drawings.

The object of my improvements is to produce a new mechanism to enable an overseam to be sewed by the use of any ordinary sewing-machine, so that the two adjacent edges of goods to be united shall substantially abut against each other after the seam is formed and the goods are straightened, to avoid any unnecessary rib or projection of the edges of the cloth beyond the seam, and to make a smooth union of the edges.

In the accompanying drawings, illustrating my improved attachment, Figure 1 is a plan view of my improved attachment. Fig. 2 is a similar view, showing the parts in a similar position. Fig. 3 is an end view, partly in section, on the line 3 3 of Fig. 1. Fig. 4 is a side elevation, with the guide-plate A in section. Fig. 5 is an elevation from the opposite side from that shown in Fig. 4; and Fig. 6 is a similar view, partly in section.

A indicates a guide-plate, provided upon the side next the needle of the sewing-machine, as usual, with an upwardly-projecting flange or plate, B.

C indicates a clamp of any suitable character for securing the guide-plate adjustably to the bed-plate of a sewing-machine.

D indicates a supplemental presser-foot, pivoted to the flange B of the guide-plate at E, and provided with a spring, F, tending to throw it up away from the bed-plate of the machine, so as to follow the upward movement of the main presser-foot, and with a stop-pin, F', to limit its upward movement. The presser-foot D is provided with a recess, D', for the purpose hereinafter designated.

G indicates a ratchet-wheel, provided with teeth H, and with pins I, turning on its axle K, fixed in the guide-plate.

L indicates a pushing-lever, pivoted at M, and provided with the spring N, bearing against the flanged guide-plate. This lever is notched

at one end, O, so as to receive successively the pins I, which are suitably shaped to enter the notch and remain there a suitable time. The lever is also notched or otherwise suitably shaped at the other end, P, to enter the recess 55 D' in the presser-foot, and engage with the edges of the cloth to be joined and push them to one side.

Q indicates a lever, consisting of two parts, Q' and S. The lower part of the lever proper is pivoted at R to the flange of the guide-plate, and the upper part, or operating-arm, S, is pivoted at T to the part Q', between its ends, and is adjustable thereon by means of a set-screw, U, working in a slot, V, formed in 65 the arm.

W indicates a branch of the arm S, secured thereto adjustably by a set-screw, X. The adjustability of the operating-arm S and its branch W is for the purpose of readily accommodating the attachment to different machines having different lengths of stroke of their needle-arms.

To the lower or shorter end of the lever Q is applied a spring-pawl, Y, adapted to engage 75 with the teeth of the ratchet-wheel G and turn it the distance of one tooth at a time.

In order to apply this improved overseaming attachment to a sewing-machine, it is necessary that a pin or a suitable projection from the needle-bar be provided to extend into the space Z between the extremity of the operating-arm and its branch. In most machines the needle-screw will answer the purpose, and no special pin need be provided. It is also 80 necessary that the supplemental presser-foot be placed under the presser-foot of the machine to which the attachment is applied, or that the presser-foot of the machine be provided with a recess similar to the recess D'. 90

The operation of this attachment is as follows: It is applied to the bed-plate of the sewing-machine in suitable relation to the goods to be united by overseaming and to the needle. The goods are laid one piece over another, 95 with the edges parallel and abutting against the flange of the guide-plate, so that each stroke of the needle desired to pass through the goods will be a suitable distance from the edge. Now, normally, every stitch of the nee- 100

dle would be taken through the goods; but by the operation of my attachment, before the needle descends to make every alternate stitch, the edges of the goods are pushed aside out of the path of the needle, so that one-half of the 5 stitches will pass through the goods at a suitable distance from the edges, and the other half of them, alternately, will pass outside of or past the edges of the goods, thus forming a perfect overseam. This movement of the 10 goods out of the path of the needle is accomplished as follows: When the needle-arm rises, it lifts the operating-arm and lever Q, causing the pawl Y to engage with one of the teeth of the ratchet-wheel and move it a distance equal 15 to the width of the tooth. Now, the number of pins upon the ratchet-wheel is just equal to one-half the number of the teeth of the wheel. The result is that this movement of the wheel 20 the distance of one tooth causes one of the pins to impinge against the end of the pushing-lever L, acting as a cam, and move that end so that it will engage by its notch with the pin, and there stop. At the same time 25 the other end of the lever, by its notch or other suitable conformation, will be caused to enter the recess D' in the presser-foot, and push that part of the edges of the goods opposite to the needle aside, just out of the path of the needle. 30 As the needle-bar descends, the operating-arm is brought down, and the spring-pawl Y is brought into position to engage with another tooth of the ratchet-wheel. When the needle-bar again rises, it causes another movement of 35 the ratchet-wheel the distance of the width of one of its teeth, which throws the pin out of the notch of the lever L, and permits the end of the lever to pass in between the pins. This releases the pressure of the opposite end of the 40 lever upon the edges of the goods, which brings the goods into position under the needle for the next stroke. The parts must of course be so adjusted, and their movements so timed, that the needle shall leave the cloth before the 45 pusher begins to move the cloth out of its path. Thus it will be seen, by this simple mechanism for alternately pushing in out of the path of the needle, and then permitting the restoration of the goods by their own tension, 50 caused by the feed, the stitches are taken with certainty, alternately, through the goods and outside of the goods, so as to form a perfect overseam. It will not, in all cases, be necessary to use the auxiliary presser-foot D, as the 55 ordinary presser-foot may be formed with a recess to accommodate the end of the pusher-lever.

I do not confine my invention to the precise form of mechanism herein described, because, without departing from its substance, considerable modifications of mechanical devices may be made for practicing it.

What I claim to be new, and desire to secure by Letters Patent of the United States, is—

1. An over-seamer for sewing-machines, consisting of the combination of the bed-plate, the vertically-reciprocating needle, means for holding the goods to be operated upon on both sides of the needle, means for feeding forward the goods, and the pushing-lever for moving that part of the edges of the goods opposite to the needle out of the path of the needle at every alternate stroke of the needle-bar, so that a stitch is alternately made in the goods and outside the edges of the goods, thereby forming an overseam, substantially as set forth.

2. The combination, with the bed-plate of a sewing-machine, of the vertically-reciprocating needle, means for holding the goods to be operated upon on both sides of the needle, means for feeding forward the goods, the guide-plate mounted on the bed-plate, the ratchet-wheel pivoted thereto, the pins carried by the wheel, which are equal to half the number of its teeth, and the pushing-lever mounted on the guide-plate, which is operated by the pins in the ratchet-wheel, whereby that part of the edges of the goods opposite the needle is moved out of the path of the needle at every alternate stroke of the needle-bar, so that a stitch is alternately made in the goods and outside the edges of the goods, thereby forming an overseam, substantially as set forth.

3. An overseaming attachment for sewing-machines, consisting of the combination of the guide-plate, the ratchet-wheel mounted thereon, the pins carried by the ratchet-wheel, (equal to half the number of teeth in the ratchet-wheel,) the lever Q, for operating the ratchet-wheel, the pusher-lever, which engages with the pins on the ratchet-wheel, and the recessed presser-foot mounted on the guide-plate, the several parts being adapted and arranged substantially as set forth.

In testimony whereof I have hereunto subscribed my name this 9th day of June, A. D. 1883.

WILLIAM F. VEBER.
